[57] **CLAIM**

The ornamental design for a "hand truck," as shown and described.

DESCRIPTION

FIG. 1 is a front elevational view of the "hand truck;"

FIG. 2 is a right side elevational view;

FIG. 3 is a back elevational view;

FIG. 4 is a top view;

FIG. 5 is a bottom view; and,

FIG. 6 is a perspective view from the left side.

The left side elevational view is a mirror image of the right side.

The broken lines are for illustrative purposes only and form no part of the claimed design.
